UNITED STATES PATENT OFFICE.

LEON WYGODSKY, OF NEW YORK, N. Y., ASSIGNOR TO WYGODSKY ENGINE COMPANY, OF NEW YORK, N. Y., A CORPORATION OF DELAWARE.

INTERNAL-COMBUSTION ENGINE.

1,076,619.

Specification of Letters Patent.

Patented Oct. 21, 1913.

Application filed April 8, 1910, Serial No. 554,136. Renewed March 14, 1913. Serial No. 754,355.

To all whom it may concern:

Be it known that I, LEON WYGODSKY, a subject of the Czar of Russia, and a resident of the city of New York, in the county of New York and State of New York, have invented certain new and useful Improvements in Internal-Combustion Engines, of which the following is a specification.

This invention relates to improvements in internal combustion engines, and the object of this invention is to provide a means for igniting the charge of combustible mixture in internal combustion engines and is especially adapted for that type in which fuel is injected at the end of the compression stroke when the compression is not high enough to ignite the charge by itself, a sufficient amount of heat being added by the present device to obtain automatic ignition of the charge.

A further object of my invention is to protect the surfaces from the atmosphere as much as possible, and also to provide means whereby the degree of temperature of the ignition device may be varied within certain limits.

A further object of this invention is to provide means whereby the heated tube will not lose its heat by conduction.

A further object is to construct the device in such a form that it may be used in combination and as a part of an oil spraying device, so that its heated surface may be located in proper coöperative relation with said spraying device.

A further object is to provide a separate article of manufacture of this character which may be kept on hand in the engine room and available of immediate use in case anything should happen to the duplicate device in use, and also as a device which may be used on any gas engine in place of the usual spark plug, or to convert a gas engine into an oil engine.

Referring to the drawings which form a part of this specification, Figure 1 represents a vertical section of an oil sprayer casing and igniter combined. Fig. 2 is an end view of the same partly in cross section on lines *a*—*b* of Fig. 1. Fig. 3 is a vertical sectional view through an ignition tube which is designed to work with two spray nozzles instead of one. Fig. 4 is a cross sectional view taken on line *c*—*c* of Fig. 3. Fig. 5 is a vertical sectional view of another modification

designed for use with two sprayers. Fig. 6 is an end view of the construction shown in Fig. 5. Fig. 7 is a vertical sectional view of another form in which two sprayers are used. Fig. 8 is an end view of the construction illustrated in Fig. 7. Fig. 9 is still another form being shown in plan section, and Fig. 10 is a side view of the same shown partly in section.

Referring by numerals to the drawings, 1 indicates the casing of the sprayer device, and 2 the sprayer located therein. In U. S. Patent No. 971,954 dated October 4, 1910, I have illustrated and described one suitable form of sprayer for use in this device. 2' designates the nozzle of the sprayer. In front of this casing, and connected thereto, is the ignition device 3, which is a tubular body, the interior surface of which communicates with the atmosphere through two 70 separate channels indicated by 4, the lower one of which serves for the insertion of a burning torch 5, which is diagrammatically represented, the heat from said torch flowing upward through said heating device and 80 escaping through the upper channel or passage 4 to the atmosphere.

When the lighted torch 5 is inserted in the bottom passage 4, the flames from the torch will heat the inside of the hollow 85 ignition tube, bringing its walls to a temperature sufficient to ignite a charge of fuel in the combustion chamber of an engine. In this manner it is possible to heat from the outside a body inclosed in the combustion chamber without the use of electricity and without exposing the heated walls to the atmosphere.

In Fig. 1 is shown how the spray of fuel issuing from the sprayer 2, is acted upon by the heated walls of the ignition body 3 by means of which the spray is ignited. This ignition body 3 is out of the path of the main portion of the spray-stream emitted from the nozzle, and contacts, at the 100 most, with the outer portion only of such spray stream, and therefore does not interfere with the normal development of the spray stream and with the splitting up of the oil, as a result of the spraying action, 105 into drops of extreme minuteness. Heretofore most ignition devices of the hot tube variety have been located directly in the path of the oil-jet or oil-spray, and as a result of such location have prevented the normal de- 110

development of the jet or spray stream. When such jet or spray stream strikes perpendicularly, or nearly so, against an obstruction, such as air ignition tube, there is a tendency for the oil to form a deposit on such obstruction, which deposit if formed is extremely detrimental. There is, moreover, a tendency in such cases for the oil drops to recombine into much larger drops; so interfering with good combustion and rapid combustion. In the operation of an engine fitted with my ignition device arranged as shown, and in which the ignition tube 3 embraces or envelops the flaring spray stream, only the outer portion of the most of the spray stream encounters the tube 3, and encounters it approximately tangentially, since the annulus 3 flares outwardly as shown. As a result, there is no tendency to deposit liquid in material quantity on the ignition body 3, but to the contrary, drops of liquid which may touch the surface of that ignition body are swept therewith and therefrom, by the velocity of the stream, before there is opportunity for the deposit of carbon from such particles on the ignition body. The normal development of the spray-stream is not interfered with, the particles of oil are not caused to recombine into larger drops, and therefore rapid and complete combustion is favored.

To facilitate the heating of the igniter, the same is insulated from the water cooled parts of the casing by gaskets 6 which are of a refractory and non-conducting material, such for illustration as asbestos. This ignition device may replace the vaporizers of oil engines as the fuel injected inside the combustion chamber will ignite at once on coming in contact therewith, without preliminary vaporization. Of course this suggests an oil engine giving a so-called constant pressure diagram *i. e.* combustion in the cylinder without an appreciable rise of pressure. Now it is easily understood that an engine supplied with such a device is capable of self-starting by spraying in fuel past this heated ignition device in a charge of pure air in the combustion space of the engine, it being understood of course that the crank of the engine has been placed above the dead center of the working stroke in the so-called starting position.

After the engine is started, the heat of combustion is quite sufficient to keep the igniter at an ignition temperature without the burning torch. If it is required to vary the temperature of the igniter, one or both channels 4 may be kept open to their full area and then a convection current of air will pass through the igniter keeping it cool, or by partly closing the channels 4, by means of the valves 7, the igniter may be kept more or less hot. The valves 7 are simply valves which are made sufficiently

wide to cover the ends of the channels 4 as will be readily understood and to swing on the screws 7. The passages 8 lead to and from a water chamber indicated by 8' which are used for the purpose of keeping the casing as cool as possible, so that the oil passing through the sprayer parts will not become too hot.

In Fig. 2, a channel 9 is indicated and is used for carrying the fuel supply from the exterior of the casing to the sprayer 2.

In Figs. 1 and 2, the heater or ignition portion of the device indicated by 3 is shown as a circular tube provided with a base plate 11 to cover the insulating material 6, and serving at the same time as a means for fixing the heater 3 to the sprayer casing by means of screws or studs passing through special holes 10 in the casing. By reason of the fact that the channels 4 for the introduction of burner 5 and for the escape of the products of combustion of the heating flame, extend from the rear of the casing 1 of the spraying device, to the ignition device 3, the application of this spraying and ignition device to an engine cylinder and its removal therefrom, is rendered a very simple matter; no ports in the walls of the engine cylinder other than the one port or opening into which the casing 1 fits, being required.

The remaining figures of the drawings show different forms of the ignition device designed to suit special conditions where two sprayers are used together.

2 indicates the sprayer, 3 the tube of the igniter chamber of a circular construction as shown in Figs. 1 and 2, or elliptical as illustrated in Figs. 3 and 4, or double circles as illustrated in Figs. 5 and 6, or S-shaped as illustrated in Figs. 7 and 8, or U-shaped as illustrated in Figs. 9 and 10, but, whatever the form may be, they are all provided with two passages indicated by 4, one of which the heat is introduced into and through the other of which the products of combustion may escape through the corresponding passages 4 in the casing, and each is provided with sole plates or flanges 11 which register with the corresponding passage in the sprayer casing. In these flanges 11 are also holes 10 for the fixing screws or studs.

It is of course understood that I may change the form of the casing and the igniter portion to suit the number of sprayer nozzles used according to the requirements of any particular case without departing from the invention disclosed, but

What I claim as new and desire to secure by Letters Patent is:

1. A new article of manufacture comprising a casing having an oil spraying device and a nozzle, a tubular igniting body connected to one end thereof, said casing having two passages extending longitudinally there-

5 through and parallel with each other, each of which is in open communication at one end with the interior of said tubular igniting body, and forming a single conduit the ends of which are located at the same end of the casing.

2. A new article of manufacture comprising a casing having an oil spraying device and a nozzle, a tubular igniting body connected to one end thereof, said casing having two passages extending longitudinally therethrough and parallel with each other, each of which is in open communication at one end with the interior of said tubular igniting body, and forming a single conduit the ends of which are located at the same end of the casing, and means for heating said igniting body.

20 3. A new article of manufacture comprising a casing having an oil spraying device provided with a nozzle, adapted to be inserted into an opening formed in the cylinder of an internal combustion engine, and a tubular ignition device connected to the 25 inner end of said casing, the body of which is located out of alinement with the axis of said nozzle; and means for heating the interior surface of said ignition device.

4. A new article of manufacture comprising a casing having an oil spraying device provided with a nozzle, adapted to be inserted into an opening formed in the cylinder of an internal combustion engine, a tubular ignition device connected to the inner end of 35 said casing, and extending around said nozzle at a short distance therefrom, and means for heating the interior surface of said ignition device.

5. A new article of manufacture comprising a casing and a tubular igniting body connected to one end thereof, said casing having two passages extending longitudinally therethrough and parallel with each other, each of which is in open communication at one end with the interior of said tubular igniting body, and forming a single conduit the ends of which are located at the same end of the casing, and valve controlling means for said conduit.

45 6. A new article of manufacture comprising a casing adapted to be connected to an engine cylinder having two separate passages therein, a tubular igniter device having two openings therein arranged in open communication with said passages, said casing having a spray nozzle located adjacent to said tubular igniter device and in cooperative relation therewith, the body of which is located out of alinement with the 55 axis of said nozzle.

7. A new article of manufacture comprising a casing adapted to be connected to an engine cylinder having two separate passages therein, a tubular igniter device having two openings therein arranged in open

communication with said passages, said casing having a spray nozzle located adjacent to said tubular igniter device and in coöperative relation therewith, the body of which is out of alinement with the axis thereof, a heat insulating material located between said casing and said igniting device. 70

8. A new article of manufacture comprising a casing adapted to be connected to an engine cylinder constructed to fit in the head of the cylinder of an internal combustion engine, a tubular igniting device connected to said casing and constructed to be supported within said combustion chamber, said casing having a nozzle located in coöperative relation with said igniting device, the axis of which is out of alinement with the body of said igniting device, for the purpose set forth. 75

9. In combination, a separate article of manufacture comprising a casing adapted to be connected to an engine cylinder, a tubular ignition device located at one end of said casing and carried thereby, and the body of which is arranged concentric with the axis thereof substantially as shown and the interior surface of which is in open communication with the atmosphere, and means for heating the interior surface of 80 said tubular device for the purpose set forth. 85

10. In combination, a separate article of manufacture comprising a casing adapted to be connected to an engine cylinder, a tubular ignition device located at one end of said casing and carried thereby and the body of which is arranged concentric with the axis thereof substantially as shown and removably secured thereto, means for heating the interior surface of said tubular device for 105 the purpose set forth, and a heat insulating means located between said casing and said tubular element. 100

11. A new article of manufacture comprising a casing and a tubular igniting body connected to one end thereof, said casing having two passages extending longitudinally therethrough and parallel with each other, each of which is in open communication at one end with the interior of said 110 tubular igniting body, and forming a single conduit the ends of which are located at the same end of the casing, and a spray device located between said passages in the casing and having the axis of its discharge aperture out of alinement with said tubular igniting body. 115

12. An ignition device comprising a tubular body having a flanged portion serving as a base plate connected therewith and having two openings which communicate with the interior of said tubular body and means for heating the interior of said tube. 125

13. A new article of manufacture comprising a casing having a central bore and 130

4. A new article of manufacture comprising a casing having at one end thereof, a spraying device located in said bore, a tubular igniting body connected to one end of said casing and located at one side of said nozzle and out of line of the axis of said spraying device, but located adjacent thereto, said casing having two passages extending therethrough and in open communication with the interior of said tubular igniting body, means for heating the interior of said tubular igniting body, and means for controlling the area of one of said passages in said casing.

14. A new article of manufacture comprising a casing having a central bore and a spray nozzle located at one end thereof, a spraying device located in said bore, a circular tubular igniting body connected to one end of said casing and located at one side of said nozzle and concentric therewith adjacent thereto, said casing having two passages extending therethrough and in open communication with the interior of said circular tubular igniting body, means for heating the interior of said circular tubular igniting body, and means for controlling the area of one of said passages in said casing.

15. A new article of manufacture comprising a casing adapted to be connected to an engine cylinder, and a tubular igniting body connected to one end thereof, said casing having two passages extending therethrough and connected with each other through said tubular igniting body and forming a single conduit, and a spray nozzle located adjacent to said igniting body and carried by said casing at one end thereof.

16. A new article of manufacture comprising a casing adapted to be connected to an engine cylinder, and a tubular igniting body connected to one end thereof, said casing having two passages extending therethrough and connected with each other through said tubular igniting body and forming a single conduit, and a spray nozzle located adjacent to said igniting body and carried by said casing at one end thereof, and means extending into one of said passages for heating said tubular body.

17. A new article of manufacture comprising a casing and a tubular igniting body connected to one end thereof, said casing having two passages extending therethrough, each of which is in open communication at one end with the interior of said tubular igniting body, and forming therewith a single conduit the ends of which are located at the same end of the casing, and a spray device located between said passages in the casing and having the axis of its discharge aperture out of alignment with said tubular igniting body.

18. A new article of manufacture com-

prising a casing having an oil spraying device and a nozzle, a tubular igniting body connected to the one end of said casing, said casing having two passages extending therethrough, each of which is in open communication at one end with the interior of said tubular ignition body and forming with the passage therein a single conduit, said tubular body being located so as not to be intersected by the axial line of said casing and nozzle.

19. A new article of manufacture comprising a casing having an oil spraying device located and extending through the center thereof and provided with a nozzle at the inner end thereof, an igniting body connected to said casing at the inner end and having a passage therethrough and located adjacent to said nozzle, the axis of said passage through said igniting body being arranged out of alignment with the axis through said nozzle, said casing having two passages extending therethrough, the inner ends of which are in open communication with the passage through said ignition body, thereby forming a single, continuous conduit, the ends of which are located at the same end of the casing.

20. The combination with a spray nozzle, of means for igniting the spray emitted by said nozzle comprising a heating body in proximity to the outer portion of the path of the spray-stream emitted by said nozzle, and out of the path of the major portion of said stream and flaring outwardly in the direction of emission of the spray-stream from its point of closest proximity to that spray-stream, and arranged to be heated by a source of heat other than the combustion of the fuel in such spray-stream.

21. The combination with a spray nozzle, of means for igniting the spray emitted by said nozzle comprising a hollow heating body in proximity to the outer portion of the path of the spray-stream emitted by said nozzle and out of the path of the major portion of the said stream and flaring outwardly in the direction of emission of the spray stream from its point of closest proximity to that spray stream, and provided with means for the introduction of a heating flame and for the escape of the products of combustion of such flame.

22. The combination with a spraying device adapted for connection to an engine cylinder and provided with a spray nozzle, of means for igniting the spray-stream emitted by said nozzle comprising a body surrounding and spaced well away from the orifice of said nozzle and located out of the path of the major portion of said spray-stream, and flaring outwardly, in the direction of emission of the spray-stream, from its point of closest proximity to said spray stream, and

arranged to be heated by a source of heat other than the combustion of the fuel in such spray-stream.

23. The combination with a spraying device adapted for connection to an engine cylinder and provided with a spray nozzle, of means for igniting the spray stream emitted by said nozzle comprising a hollow annular body surrounding and spaced well away from the orifice of said nozzle and located out of the path of the major portion of said spray stream, and flaring outwardly, in the direction of emission of the spray stream, from its point of closest proximity to said spray stream, and provided with ports for the introduction of a heating flame into the interior passage of said annulus, and for the escape of the products of combustion of said flame, said spraying device having passages, corresponding to the said ports of the annulus, and extending from the rear of said spraying device into communication with the said ports, and valve means for restricting or closing at will one of said passages.

24. The combination with a spraying device adapted for connection to an engine cylinder and provided with a spray nozzle, of

means for igniting the spray stream emitted by said nozzle comprising a hollow annular body surrounding and spaced well away from the orifice of said nozzle and located out of the path of the major portion of said spray-stream, and flaring outwardly, in the direction of emission of the spray-stream, from its point of closest proximity to said spray-stream, and provided with ports for the introduction of a heating flame into the interior passage of said annulus, and for the escape of the products of combustion of said flame, said spraying device having passages, corresponding to the said ports of the annulus, and extending from the rear of said spraying device into communication with the said ports, and valve means for restricting or closing at will one of said passages.

Signed at New York city, in the county of New York and State of New York this sixth day of April A. D. 1910.

LEON WYGODSKY.
